UNITED STATES PATENT OFFICE.

ARCHIBALD GRIEVE, OF WESTPORT, CONNECTICUT, ASSIGNOR TO CHARLES H. KEMPER, INC., OF WESTPORT, CONNECTICUT, A CORPORATION OF CONNECTICUT.

FUSE

Application filed February 4, 1921. Serial No. 442,516.

To all whom it may concern:

Be it known that I, ARCHIBALD GRIEVE, a subject of the King of Great Britain, residing at Westport, in the county of Fairfield and State of Connecticut, have invented certain new and useful Improvements in Fuses, of which the following is a specification.

My invention relates to electric fuses, and particularly to renewable cartridge fuses of the clip type. Among the objects of my invention may be particularly mentioned—one, the provision of a construction in which a rated end of the fuse strip may be carried with safety to exposed position on the interior of the fuse casing; two, an end construction in which there is but a single detachable member; three, a construction using a draw-up screw ferrule having means to prevent the escape of gases to the threaded area of the ferrule and its complementary part of the fuse casing; four, an end construction in which a circuitous gas escape passage is provided by the detachable ferrule element; five, a contact member freely carried by the end ferrule to engage the bent-over end of the fuse strip, but having a swiveling connection with the ferrule so as to protect the fuse strip end against which it bears from rupturing strains, and at the same time affording by its loose engagement with the ferrule a gas vent; six, various details of improved construction hereinafter pointed out or shown in the accompanying drawings, in which—

Fig. 1 is a broken side elevation of a fuse in which my invention is embodied in one form, the end cap at the left-hand end of the fuse being shown detached;

Figs. 2, 3 and 4 are end elevation and sections, respectively, on the lines 2—2, 3—3 and 4—4, Fig. 1; and

Fig. 5 is a longitudinal section at right angles to Fig. 1.

In certain respects the present construction is akin to that illustrated in my application Ser. No. 442,515, filed herewith on the blade type fuse, although, like that, it is susceptible of modification in various particulars, while still retaining the underlying features to which the invention is directed. As illustratively embodied in the construction shown in the accompanying drawing, the fuse comprises a tubular casing 6 of fiber, or other insulating material, having

sufficient mechanical strength to withstand the strains imposed upon it on the blowing of the fuse. At the opposite ends of the casing are metal bushings 7 and 8 having reduced necks, which are forced into the ends of the casing and riveted thereto at 9. These necks are preferably externally serrated, not only to grip the fiber casing mechanically, but also to prevent the escape of gas through the joint, to the injury of the fiber, on the blowing of the fuse strip. Adjacent the shoulder 10 of the bushing, which abuts against the end of the casing 6, the bushing is threaded at 11 to receive the detachable ferrule 12.

The slightly reduced cylindrical outer ends of the bushing are provided with closure diaphragms 13 and 14, on which at 15 and 16, respectively are pivoted shutters 17 and 18. The latter substantially close the end openings 19 in the diaphragms 13 and 14, through which the opposite ends of the fuse strip 20 are passed to the exterior of the bushings. As will be noted from Figs. 2 and 3, the portion of the shutter overlying the opening 19 is provided with a straight edge 21, which in adjusted position, determined by the stud X, lies parallel to one edge of the opening 19, but spaced slightly therefrom to afford a narrow exit passage 22, which is substantially filled by the fuse strip as it passes out therethrough from the fuse chamber. The shutter is preferably so shaped that its margin 23 conforms to the contour of the bushing end.

In order to afford a suitable contact area, the projecting ends of the fuse strip are angled over the straight edges 21 of the shutters and overlie the outer faces of the latter. At one end of the fuse the shutter is notched at 24 to permit an extension 25 of the fuse strip to be turned back therethrough between the skirt of the ferrule 12 and the outer face of the bushing 7, in which a shallow groove 26 is formed in register with a continuation 27 thereof in the fuse casing to receive the end of the fuse strip. The latter bears a rating indication 28, which is thus exposed on the exterior of the fuse casing beyond the edge of the skirt of the ferrule 12, and is readily observed by an inspector.

To prevent escape of gases through the groove 26, 27, the latter is of such width

and depth that the end of the fuse strip fills it and thus projects outward into the area of the threads 29 on the ferrule. The engagement of the fuse strip end by the 5 threads 29 of the ferrule effectually baffles the escape of gas at this point, if it does not actually seal the passageway. Furthermore, the fit of the reduced end of the bushing with the inner face of the skirt of the 10 ferrule is as snug as possible, and may be readily made so tight that the escape of gas to the threaded area of the bushing and ferrule is rendered practically impossible.

It will be noted that the gases escape 15 from the fuse chamber principally, if not entirely, at the narrow passage 22, through which the fuse strip emerges and thus has a restricted entry into the expansion chamber 20 30 formed between the end of the bushings and the end of the ferrule. From this chamber 30, in which the gases are cooled by expansion, they escape through a circuitous passage in contact with metallic cooling surfaces. To effect this, on the 25 closed end of the ferrule 12 is mounted a gas deflecting washer 32 of slightly less diameter than the internal diameter of the cap. On the outer face of the washer are formed channels 33, or other venting passageways, 30 which lead to a central orifice 34 in the end of the ferrule. This orifice is largely, but not completely, obstructed by the retaining stud 35 on the washer, which passes through the orifice and is sufficiently headed up to 35 secure the washer to the ferrule end while nevertheless affording the play in the orifice necessary to permit the latter to function as a gas escape passage. This stud may be integral with the washer, as indicated, or it 40 may be an independent member passing therethrough and riveted in position by a suitable spreading operation. Preferably associated with the washer is an inner bearing boss 36 which overlies and contacts with the bent-over end of the fuse strip when 45 the ferrule is screwed down on the bushing. Obviously, the loose attachment of the washer to the end of the cap permits the boss 36 to remain stationary in swiveling 50 engagement with the ferrule as the latter is screwed home on the bushing. This prevents injury by the boss to the fuse strip end which might otherwise be torn or ruptured during the screwing down of the ferrule were the washers forced to rotate 55 with the ferrule.

In assembled position the ferrules 12 are screwed down hard upon the end bushings 7 and 8, thus not only establishing good electrical contact with the bent-over ends of the fuse strips, but also firmly pressing the shutters 17 and 18 against the end diaphragms 13 and 14 of the bushings and positioning the skirt of the ferrule in engagement with the reduced end of the bush-

ing. This renders the closure of the fuse chamber complete, except for the restricted openings between the shutters and the diaphragms at the points at which the ends of the fuse strip pass out of the fuse chamber. 70 On the blowing of the fuse, the gases emerge through this passage to the expansion chamber 30, where they are cooled by expansion and reduced in pressure. From the expansion chamber the gases are constrained to 75 pass outward around the margins of the washers 32 into the channels 33, or the like, through which they flow, in cooling contact with the cap ends 31, to the vents 34. Their heat and pressure are now so reduced or 80 dissipated that no danger attends their escape.

To remove the fuse strip it is merely necessary to unscrew the ferrules 12, carrying the washers 32, swing the shutters 17 85 and 18 outward to the position indicated in dotted lines in Fig. 3, whereupon the burnt fuse strip ends may be removed through the openings 19 in the bushing, a new fuse strip inserted therethrough, the shutters swung back to closure position and the ferrules again adjusted. It will be noted that there are no loose washers or parts apt to be lost or misplaced, the shutters 17 and 18 being permanently attached to the diaphragms 13 and 14, and the washers 32 being permanently attached to the ferrules 12. 90

The provision of the exposed indicator 28 on the fuse renders inspection of the latter simple, and insures the use of a fuse strip of proper capacity for the casing. While it is intended that within a given range, fuses of different capacity may be used with a single casing construction, the 100 variation of the thickness of the fuse strips is not sufficient to render the seal at the grooves 26, 27 ineffective. Were it attempted, however, to insert a fuse strip of 105 greater capacity than that for which the casing is designed, its greater thickness would 110 make it impossible to screw down the ferrule on the bushing.

The construction as a whole is simple, rugged and serviceable, with a minimum of 115 detachable parts, and no loose parts likely to be lost or misplaced during the renewal of the fuse strip. As above stated, various modifications of construction which embody the underlying thoughts of what I claim as my invention, will readily occur to those skilled in the art, and I do not limit my invention to the precise structure illustrated and above described. 120

I claim—

1. A cartridge fuse having a detachable end closure cap, and permanently secured therein in loose relation a gas-deflecting and heat-absorbing washer. 125
2. A cartridge fuse having a detachable 130

end closure cap, and permanently secured therein in loose relation a gas-reflecting and heat-absorbing washer, said washer having a loose engagement with the cap to afford a 5 gas escape.

3. A cartridge fuse having a detachable end cap, and permanently secured therein in loose relation a gas-deflecting and heat-absorbing washer affording a vent passage 10 between the outer face of the washer and the inner face of the cap.

4. A cartridge fuse having a detachable end cap, and permanently secured within the same in loose relation a gas-deflecting 15 and heat-absorbing washer affording a vent passage between the outer face of the washer and the inner face of the end cap, said washer being of less diameter than the internal diameter of the cap.

20 5. In a cartridge fuse, a detachable end cap, in combination with a washer carried thereby on its inner face, and a boss on the inner face of the washer for making contact with the end of a fuse strip.

25 6. In a cartridge fuse, a detachable screw cap, and carried thereby a fuse contacting member freely swiveling in the cap.

7. A cartridge fuse having a substantially closed fuse chamber, and means for supporting in exposed position at one end thereof the bent-over end of a fuse strip, in combination with a detachable end cap, and loosely carried thereby a contact member adapted to engage the end of the fuse strip.

30 8. A cartridge fuse having a substantially closed fuse chamber, and means for supporting in exposed position at one end thereof the bent-over end of a fuse strip, in combination with a detachable end cap, and freely carried thereby a venting contact member

adapted to engage the end of the fuse strip.

9. A cartridge fuse having a substantially closed fuse chamber, and means for supporting in exposed position at one end thereof, the bent-over end of a fuse strip, in combination with a detachable end cap, a washer carried thereby within the cap, and a boss on the inner face of said washer adapted to space the latter from the end of the fuse chamber to afford an expansion chamber for gases escaping from the fuse chamber on the blowing of the fuse.

10. A cartridge fuse having a substantially closed fuse chamber and means for supporting at one end thereof the bent-over end of a fuse strip, in combination with a detachable end cap, a washer carried by said cap and lying within the same, and a boss on the inner face of said washer to engage the bent-over end of the fuse strip and serving to space the washer from the end of the fuse chamber to afford a gas expansion chamber, together with means affording a gas escape passage around the periphery of the washer and between the outer face of 65 the latter and the cap.

11. A cartridge fuse having a tubular casing of insulating material, a metallic bushing secured at the end of the casing, said bushing having an external screw thread and a reduced area at the outer end of said bushing beyond the screw thread, in combination with a detachable screw cap adapted to engage the threaded area of the bushing, and having a snug fit with the reduced end 70 of the bushing to prevent the escape of gas thereby to the threaded area.

In testimony whereof I have signed my name to this specification.

ARCHIBALD GRIEVE.
